Primary Examiner—Catherine Tuttle

(74) Attorney, Agent, or Firm—Fulbright & Jaworski L.L.P.

(57) **CLAIM**

The ornamental design for a container base, as shown and described.

DESCRIPTION

FIG. 1 is a top perspective view showing my new design for a container base;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is bottom view thereof.
